[57] ABSTRACT

A new and distinct variety of Chrysanthemum plant. The new plant is characterized by its flat capitulum form, anemone capitulum type, pinkish white ray floret color, darker purple contrasting disc floret color, a diameter across face of capitulum of 4.0–7.0 cm, upright to spreading branching pattern with ca. 3–5 breaks after a single pinch, a flowering response of 59 to 63 days from the start of short days, and a plant height for a 6.5 inch (16.5 cm) pot of about 40–52 cm with 1–2 applications of B-9 at 2500 ppm.

1 Drawing Sheet

1

BACKGROUND

1. The Field of the Invention

This invention relates to Chrysanthemum plants. More particularly, the present invention comprises a new and distinct cultivar of Chrysanthemum plant, botanically known as *Dendranthema grandiflora* and hereinafter referred to by the cultivar name "Definite Eyes."

2. Background of the New Plant

Definite Eyes, identified as 87.3111, was originated from a cross made by Jack Van Der Knaap in a controlled breeding program at De Lier, Holland in 1986.

The female parent of Definite Eyes was unnamed selection #86.2409, and the male parent was unnamed selection #86.2439.

Definite Eyes was discovered and selected as one flowering plant within the progeny of the stated cross by Jack Van Der Knaap in November of 1987 in a controlled environment at De Lier, Holland.

The first asexual reproduction of Definite Eyes was accomplished when vegetative cuttings were taken in January of 1988 in a controlled environment at De Lier, Holland by technicians working under the direction and supervision of Jack Van Der Knaap.

SUMMARY OF THE INVENTION

The basic characteristics which have been repeatedly observed in Definite Eyes and which, in combination, distinguish this Chrysanthemum plant over related known varieties and its antecedents are:

1. Flat capitulum form.
2. Anemone capitulum type.
3. Pinkish white ray floret color.
4. Darker purple contrasting disc floret color.
5. Diameter across face of capitulum 4.0–7.0 cm.
6. Branching pattern is upright to spreading with ca. 3–5 breaks after a single pinch.
7. Flowering response is 59 to 63 days from the start of short days.

2

8. Plant height of a 6.5 inch (16.5 cm) pot is about 40–52 cm with 1–2 applications of B-9 at 2500 ppm.

Horticultural examination of controlled flowerings of successive plantings has shown that the combination of characteristics and distinctions as herein disclosed for Definite Eyes are firmly fixed and are retained through successive generations of asexual reproduction.

10 BRIEF DESCRIPTION OF THE DRAWING

FIG. 1 is a photographic print in full color showing typical inflorescence and leaf characteristics of Definite Eyes grown as a pinched spray pot mum with 5 cuttings in a 6.5 inch (16.5 cm) pot, the colors being depicted as nearly true as it is reasonably possible to make the same in a color photograph of this character.

DETAILED DESCRIPTION OF THE NEW PLANT

Definite Eyes has not been observed under all possible environmental conditions. The phenotype may vary significantly with variations in environment such as temperature, light intensity, and day length.

20 The following is a detailed description of Definite Eyes, with color terminology in accordance with *The Royal Horticultural Society Colour Chart*, except where general color terms of ordinary dictionary significance are obvious. The following observations, measurements and comparisons were made of plants grown at Nipomo, Calif. in controlled environments. Unrooted cuttings were directly stuck into 6.5 inch (16.5 cm) pots and grown in a controlled environment under the natural temperature and day length prevailing during October to December of 1990.

Classification:

Botanical.—*Dendranthema grandiflora* cv. Definite Eyes.

Commercial.—Flat anemone to be grown as a spray pot.

INFLORESCENCE

A. Capitulum:

Form.—Flat.

Type.—Anemone.

Diameter across face.—40-70 mm when fully opened.

B. Corolla of ray florets:

Color (general tonality from a distance of three meters).—Pale pink graduating to a dark purple eye.

Color.—Front: 69 D. Back: some 70 C.

Shape.—Elliptic.

C. Corolla of disc florets:

Color.—The center of the cushion is dark maroon 59A, and the other rows of the cushion are a much lighter 56C.

D. Reproductive organs:

Androecium.—Present on disc florets only; insignificant.

Gynoecium.—Present on both ray and disc florets; insignificant.

PLANT

A. General appearance:

Height.—When grown in 6.5 in. (16.5 cm) pots with 1-2 applications of B-9, the total plant height including the pot will be 40-52 cm.

Branching pattern.—Upright to spreading with 3-5 breaks after the pinch.

B. Foliage:

Color (upper surface).—147 A.

Color (lower surface).—147 B.

Shape.—See FIG. 1. Up to 6 cm long. Up to 4 cm wide.

Definite Eyes can be well distinguished from other commercial Chrysanthemum cultivars, including Autumn Eyes (U.S. Plant patent application Ser. No. 712,334, filed Jun. 7, 1991), Dark Eyes (U.S. Plant patent application Ser. No. 712,903, filed Jun. 7, 1991), Quiet Eyes (U.S. Plant patent application Ser. No. 712,052, filed Jun. 7, 1991), Tara (U.S. Plant Pat. No. 6,313), and Vibrant Eyes (U.S. Plant patent application Ser. No. 712,901, filed Jun. 7, 1991). See in this regard the data presented in Table A hereafter. Also, the blossom coloration of Definite Eyes can be readily distinguished from Cherub U.S. Plant Pat. No. 4,629), Rave (U.S. Plant Pat. No. 5,738), Franky Lane (U.S. Plant Pat. No. 6,302), and California Moneymaker (U.S. Plant Pat. No. 6,851) as described in the respective U.S. Plant Patents.

Similar traits to the other above-mentioned Eye varieties are capitulum form and type (with the exception of Quiet Eyes which is a flat daisy type), branching pattern, and the distinctly contrasting center of the disc. However, each Eye variety varies in color of the disc and ray florets, making each a unique and different cultivar.

Similar traits to Tara are capitulum form and type, and breaks/pinch. Definite Eyes, generally has more ray florets and more disc florets per flower, and the ray florets are generally longer by an average of 1 cm. Definite Eyes is approximately 4-7 days slower, and has fewer flowers per break than Tara. The coloration of the petals is very different between Tara and Definite Eyes.

TABLE A

Characteristic	Autumn Eyes	Dark Eyes	Definite Eyes
capitulum	flat	flat	flat
form			
capitulum	anemone	anemone	anemone
type			
diameter	ca. 3.4 cm	ca. 3.5-6.0 cm	4.0-7.0 cm
across face			
branching	upright	spreading	upright and spreading
pattern			
breaks/pinch	ca. 4.0	4-7	3-5
height in 6.5 in. (16.5 cm)	30-40 cm	ca. 40 cm	40-52 cm
pot with 1-2 applications of B-9			
disc floret color	golden 11 A tipped with dark maroon 59 A; eye is dark maroon 59 A	medium lavender 75 C graduating to a very dark eye of 77 A; tube 75 C	56 C on the outer petals graduating to a dark purple eye of 59 A
no. disc florets	ca. 171	ca. 145	ca. 225
length disc florets	ca. 1.0 cm	1.0-1.5 cm	up to 2 cm
ray floret color	long front: golden yellow 11 A back: pale yellow 11 B	long front: 75 C back: 75 C with a 77 B stripe down the center	long front: 69 D back: some 70 C
no. ray florets	ca. 22	24-27	average of 27.3
shape ray florets	oblong with rounded to flat tip	oblong with rounded tip	elliptic
length ray florets	1.0-1.5 cm	up to 2.5 cm	up to 4 cm
width ray florets	long	long	long
no. flowers/break	0.3-0.5 cm	up to 0.75 cm	up to 1.0 cm
leaf color	wide	wide	wide
leaf length	ca. 9.6	average of 5.16	average of 5.3
leaf width	front: 147 A back: 147 B	front: 147 A back: 147 B	front: 147 A back: 147 B
response time	ca. 7.5 cm	up to 8 cm	up to 6 cm
	long	long	long
